UNITED STATES PATENT OFFICE

JOHN B. KLEIN, OF KANSAS CITY, KANSAS

DESIGN FOR A BUILDING

Application filed November 7, 1931. Serial No. 41,654. Term of patent 3½ years.

To all whom it may concern:

Be it known that I, JOHN B. KLEIN, a citizen of the United States, residing at Kansas City, in the county of Wyandotte and State of Kansas, have invented a new, original, and ornamental Design for Building, of which the following is a specification, reference being had to the accompanying drawing, forming part thereof, in which:

The figure is a perspective view of a building, showing my new design. The front and rear of the building are similar in design.

I claim:

The ornamental design for a building, as shown and described.

JOHN B. KLEIN.
